UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

OIL-WELL PACKER.

1,109,078.

Specification of Letters Patent.

Patented Sept. 1, 1914.

Application filed March 7, 1914. Serial No. 823,174.

To all whom it may concern:

Be it known that I, PATRICK H. MACK, a citizen of the United States, residing at Bradford, in the county of McKean and State of Pennsylvania, have invented certain new and useful Improvements in Oil-Well Packers; and I do hereby declare the following to be a full, clear, and exact description of the invention, such as will enable others skilled in the art to which it appertains to make and use the same.

My invention relates generally to that class of devices termed oil well packers, used in conjunction with casing and tubing in oil or artesian wells for the purpose of shutting off the water of the higher levels from a lower portion of the well or from the oil bearing sands, and the present invention is more especially directed to the production of a packer for use in conjunction with the pumping tube to shut off water issuing from the lower strata adjacent to the oil bearing sands.

Oil well packers in general, and as commonly constructed, comprise in combination a hollow cylinder or annulus of rubber or equivalent compressible and expansible material constituting the packing, a seat or abutment within the well for the support of the hollow compressible cylinder or annulus, and means for transferring the weight of the tubing or casing to the hollow cylinder in such manner as to compress the cylinder longitudinally and expand it laterally to close the space between the tubing or casing and the wall of the well. The seat or abutment for the cylinder may have its support on the side walls of the well alone, or on the bottom and the side walls of the well. In the former case, the construction of the packer and its anchor is such that the packer and its anchor may be raised or lowered in the well, or its position in the well changed if required, by the crumbling or spalling of the walls of the well, without pulling the casing from the well; and its support is independent of the bottom of the well. In the latter case the engagement of the anchor with the walls of the well is effected through the medium of an extension of tubing below the packer resting on the bottom of the well, and consequently when change of position of the packer within the well, for any reason, becomes necessary, the tubing must be pulled from the well and the length of tub-

ing extending below the packer must be diminished or increased, as the case may require.

A string of well tubing is frequently thirty-five hundred feet, more or less, in length, and will weigh seven tons or more. In the use of wall packers with a casing, a shoulder in the bore of the well supports the casing and will prevent any extended drop thereof in case the packer fails from crumbling of the walls; but in the case of tubing the tubing is suspended and therefore in the latter case if the wall of the well crumbles the anchor fails and the tubing drops through any appreciable distance, the momentum acquired by the tubing is such that the arrest of the tubing frequently results in buckling of the tubing or in fracturing of the tubing at the joints, and an expensive and difficult fishing job, or possibly loss of the well ensues. For this reason it is deemed preferable, in the case of tubing to use an anchor which has a support on the bottom of the well, as heretofore pointed out, so that in case of crumbling of the walls of the well a scarcely appreciable drop of the tubing will follow with less or little chance of injury to the tubing, and this notwithstanding the inability to change the position of and reset the packing without pulling the tubing.

To overcome the disadvantages and objections incident to the forms of oil well packers as at present constructed and applied while retaining the advantages incident to both forms is the object of my invention, and to effect this I combine in an oil well packer, a compressible and expansible packing, an abutment therefor, means for engaging and anchoring the abutment to the side walls of the well, means for releasing and thereafter locking the abutment anchor while in the well, and a tubular extension below the anchor, said extension being movable with relation to the body of the packer whereby when the wall anchor of the packer becomes inoperative from any cause the telescoping extension may serve to arrest the descent of the abutment anchor, thereby automatically resetting the wall anchor of the packer, thus preventing injury to the tubing, and such a construction embodies the main feature of my invention.

There are other, minor, features of invention, involving the combination of particu-

lar elements whereby a highly efficient construction of the packer is obtained, all as will hereinafter more fully appear.

In the drawings chosen for the purpose of illustrating my invention, the scope whereof is pointed out in the claims, Figure 1 is a view in elevation, parts broken out, showing an oil well packer embodying one form of my invention. Fig. 2 is a longitudinal central section of an oil well packer embodying my invention, parts broken out, and of a well, showing the relation of the coacting elements to each other and to the well walls previous to setting the packer as a wall packer. Fig. 3 is a sectional view similar to Fig. 2, showing the relation of the coacting elements to each other and to the walls of the well after the packer has been set in the well. Fig. 4 is a sectional view of the lower end of the telescoping extension sleeve of the packer showing a reducing coupling which may be substituted for the one shown in Fig. 2 when the pumping tube does not extend through the packer. Fig. 5 is a transverse sectional view of the packer taken in the plane of the line 5—5 Fig. 1, and, Fig. 6 is a transverse sectional view of the packer taken in the plane of the line 6—6, Fig. 1.

Like symbols refer to like parts wherever they occur.

I will now proceed to describe my invention more fully so that others skilled in the art to which it appertains may apply the same.

In the drawings, 1 indicates a coupling collar whereby the packer is connected or coupled with a string of tubing a . This collar 1 is threaded internally as at 1^a for connection with the pumping tube above the packer, at 1^b for connection with that portion of the pumping tube a^1 which extends through the packer—when this occurs—and again at 1^c for connection with the body 2 of the packer. The collar 1 may also be externally threaded as at 1^d if desired, as a means of facilitating the grabbing of the packer in case it should become necessary at any time to fish for the packer. The pumping tubing a , a^1 is usually of two inch diameter, more or less, but the diameter of the tubing constituting the body portion 2 of the packer will be governed by the diameter of the bore of the well with which the packer is to be used.

Surrounding the body portion 2 of the packer immediately below the collar 1 is a hollow cylinder or annulus 3 of compressible material, preferably of rubber, which constitutes the packing, and immediately below the packing cylinder 3 is an annular abutment or seat 4 therefor, through which annular abutment the body 2 of the packer is freely movable downward though the movement downward of the annular abutment on

the body portion 2 of the packer is limited by a slight annular shoulder 2^a on the exterior of the body portion 2. The position of the shoulder 2^a is such as to prevent the separation of the collar 1, the packing cylinder 3 and the annular abutment 4. The annular abutment 4 tapers downward, or is in the form of a frustum of a hollow cone so as to obtain a wedge shape cross section for coaction with the slips of an anchor. 70

The lower end of the body portion 2 of the packer is provided with a collar which forms a peripheral shoulder 2^b to engage a similar shoulder on the interior of a telescoping section or sleeve extension, and a short distance 80 above its lower end the body portion 2 of the packer is provided with diametrically disposed slots 2^c of L-shape for the reception of pins on an anchor cage, the slots and pins constituting a bayonet lock for holding the 85 anchor slips out of operative engagement with the annular abutment 4. 75

5 indicates an anchor cage located below the annular abutment 4 and movable on the body portion 2 of the packer. 90

6 indicates slips loosely connected with the cage 5 by the reins 6^a and held in contact with the inclined face of the abutment 4, and out of contact with the walls of the well by semi-elliptic springs 7 one end of 95 each of said springs being secured to the cage as at 7^a while the other end bears on the rein of a slip above the movable connection of the rein with the cage 5. These springs 7 will at all times engage the side walls of 100 the well where the diameter of the well is normal, and will sustain the cage and slips in a fixed position in the well when the cage is free of the body 2 so that the body 2 can move longitudinally independently of the 105 cage. The springs also maintain the slips 6 out of engagement with the walls of the well in raising or lowering the packer when the cage is locked to the body of the packer. 110

Equally disposed around and projecting downward from the cage 5 are a plurality of lugs or projections 5^a and projecting inwardly from two oppositely located lugs 5^a are pins 5^b which enter the L-shaped slots 2^c in body 2 of the packer and prevent any 115 relative longitudinal movement of the anchor cage and packer when in the horizontal portions of said slots.

Secured below and in telescoping relation to packer body 2 is an extension sleeve 8 the upper end of which is preferably substantially in contact with the lower end of anchor cage 5 when the anchor cage is in its lowest position, and said sleeve has on its interior at its upper end a shoulder which 120 engages the shoulder 2^b on the lower end of body 2 of the packer so that the extension sleeve is suspended from the packer body 2. The lower end of the extension sleeve 8 is internally threaded as at 8^a for the reception 125 130

of a coupling member 9 for the attachment of such further length of tubing 10 as will suffice to extend from the coupling member in its proposed position in the well to within 5 a short distance of the bottom of the well. When the pumping tubing a^1 extends through the packer body 2 as shown in the several figures of the drawing this coupling member 9 will be of such character as to 10 connect with an extension tubing 10 of a diameter to permit of the free passage of the lower end of the pumping tubing a^1 , and the extension sleeve 8 and extension tubing 10 will be of such length that the bottom of the 15 cage 5 will engage the upper end of extension 8 before the end of the tubing a^1 strikes the bottom of the well. Where the portion a^1 of the pumping tubing is omitted, or does not extend through the body 2 of the packer, 20 a reducing coupling 9^a, Fig. 4, or its equivalent, may be substituted for the extension coupling 9 shown in the principal figures of the drawing.

The construction of the packer being of 25 the character hereinbefore pointed out it will be applied in the well and will operate as follows: When the anchor cage 5 is in its lowest position on body 2 of the packer and the pins 5^b are in the horizontal portions 30 of the L-shaped slots 2^c, the cage is fixed against longitudinal movement with relation to the body 2 of the packer and the abutment 4, and the packer may be inserted in the well and lowered or raised therein 35 without the anchor slips 6 engaging the walls of the well, but the elliptic springs 7 will be in frictional contact with the walls of the well. When the packer has been lowered to the desired position in the well, 40 which will be one wherein the lower end of the extension tubing 10 of the telescoping member is near the bottom of the well though not in contact therewith, the tubing a is rotated and as the anchor springs 7 are 45 in contact with the walls of the well the cage will remain stationary and the pins 5^b will eventually enter the vertical portions of the L-shaped slots 2^c, which will permit a 50 downward movement of the body 2 of the packer and will cause the conical annular abutment 4 to move downward between the slips 6 and body 2 of the packer, whereby, 55 owing to the load on the annular abutment 4, its descent will force the slips outward into a firm engagement with the walls of the well, as shown in Fig. 3 of the drawings, thus anchoring the abutment 4 on the side walls of the well. The abutment 4 being 60 thus fixed in the well the load imposed by 65 the tubing through collar 1 on the compressible cylindrical packing 3 maintains the packing expanded against the walls of the well, effectively shutting off from the lower part of the well any inflow of water from above the packing. If, however, the walls

of the well should spall or crumble so as to release the anchor and abutment, the downward movement of the anchor would be arrested by the telescoping extension member before the tubing had gained any 70 material momentum, and the bottom of the anchor cage 5 coming in contact with the upper end of the telescoping extension a little before the downward movement of the body of the packer had ceased would arrest 75 the downward movement of the anchor cage and the continued movement of the tubing would automatically reset the wall packer if the walls of the well are in condition to permit of the setting of the packer. Under 80 any conditions, the arrest of the movement of the tubing before it has acquired material momentum will prevent material injury to the tubing, pumping barrel, or packer, and by lifting and rotating the tubing until the 85 pins 5^b enter the horizontal portion of the L-slot 2^c, the anchor cage will become fixed with relation to the body portion 2 of the packer, the annular abutment 4 will be withdrawn from behind the slips, the slips will 90 reassume the position shown in Fig. 1 of the drawing, so as to avoid the walls of the well, and the packer may be raised and reset in the well where the bore of the well is of normal diameter, and this without pulling 95 the tubing or removing the packer from the well.

Having thus described my invention, what I claim and desire to secure by Letters Patent is:

1. In an oil well packer, the combination with an annular compressible packing, of a packer body, an abutment through which the packer body is movable, an anchor for anchoring the abutment on the walls of the well, means for fixing the anchor with relation to the body of the packer and releasing it therefrom while in the well, and an extension member below the anchor said member having a telescoping connection with the body of the packer.

2. In an oil well packer, the combination of a packer body, an annular packing, an abutment for the packing, said abutment and the body of the packer being relatively movable, an anchor for the abutment, said anchor and the body of the packer being also relatively movable, means for at will connecting and disconnecting the anchor and the packer body while in the well, and a pendent extension member below the anchor, said member being movable with relation to the packer body and adapted to engage the anchor.

3. In an oil well packer, the combination with an annular compressible packing, of a packer body, an abutment for the annular packing said abutment being movable with relation to the packer body, an anchor cage having slips loosely carried thereby, semi-

- elliptic springs connected with the anchor cage and bearing on the slips, said springs being adapted to engage the walls of a well, means for connecting the anchor cage to and disconnecting it from the body of the packer at will while in the well, and a pendant extension member having a telescoping connection with the lower end of the packer body.
- 10 4. In a well packer, the combination of a packer body, a suspended downward extension thereof, said extension having a telescoping connection with the packer body, an annular packing, an abutment for the annular packing, and means carried by the packer body for anchoring the abutment to the walls of a well said means being oper-

able independently of the suspended extension member of the packer body.

5. In a well packer, the combination of a 20 body member, an extension member suspended from and telescopically connected with the body member, an annular packing, an annular abutment for the packing, anchor devices for supporting the abutment 25 from the walls of a well, and spring members on the anchor for frictionally engaging the walls of a well.

In testimony whereof I affix my signature, in the presence of two subscribing witnesses. 30
